UNITED STATES PATENT OFFICE.

NATHAN RUBENSTEIN, OF NEW YORK, N. Y.

SADIRON.

1,328,766.

Specification of Letters Patent. Patented Jan. 20, 1920.

Application filed June 11, 1919. Serial No. 303,403.

To all whom it may concern:

Be it known that I, NATHAN RUBENSTEIN, a citizen of the United States, and residing at New York, New York county, and New York State, have invented certain new and useful Improvements in Sadirons, of which the following is a specification.

This invention relates to sad irons and its object is to provide a hollow iron with an inlet for a steam pipe and an outlet for the condensed water and means for releasing steam at the under surface of the iron and controlling the same at the handle and where it is adapted to be operated by the finger of the operator. The construction of the iron also permits of the effectual insulation of the operator's hand from the heat of the iron and the whole forms a simple, compact and substantial device capable of considerable wear and tear, as will be more fully described in the following specification, set forth in the appended claim, and illustrated in the accompanying drawings, wherein:

25 Figure 1 is a side elevation of the iron.
Fig. 2 is a vertical sectional view.
Fig. 3 is a rear elevation.
Fig. 4 is a plan view of the iron with the cover removed.

30 Fig. 5 is a modified detail.

Fig. 6 is a detail plan view of the operating lever.

The body 10 of the iron is of ordinary shape and of appropriate weight and has 35 passages 11 bored partly through its length with a plug at the outer end and having outlets 12 at the bottom surface of the iron, and 13 bored vertically, both communicating and the latter having a goose-neck 14 that connects the passage 11 with the interior of the iron.

40 At the rear end of the interior of the iron is a pocket 15 and through the rear of the iron and near this point extends the twin 45 pipes 16 and 17 carried by a threaded plug 18 that screws into a hole in the iron.

The pipe 17 extends downward into the pocket 15 and is adapted when the cock 19 is open to drain the condensed water that 50 is collected in said pocket and carry it off through suitable flexible piping shown in dotted lines and connected by the coupling 20.

A flexible pipe is also connected with pipe 55 16 by means of the coupling 21 and delivers live steam into the interior of the

iron and heats the same and provides the necessary steam spray for the outlets 12.

In the goose-neck 14 is a cock 22 normally closed and having an arm 23 which is 60 engaged by a fork 24 on a bell crank lever pivoted to the handle 25 by a bolt 26 and having the knob 27 in proximity to the thumb of the operator while he grasps the said handle 25 so the bell crank lever may 65 be manipulated to cause the jaw 28 of the fork to depress the arm 23.

As shown in the detail in Fig. 6 the lower jaw of the fork, 29, has an off set 30 that covers the end of a plunger 31 adapted to 70 be depressed in a socket 32 of the iron and supported in its extended position by the coil spring 33 but both throwing back the bell crank lever on its pivot until arrested by the stop 34 on the handle. 75

Another form of manipulator for the admission of steam to the sprayer is shown in Fig. 5 where the knob 35 or flat piece is forced outward by the thumb of the right hand of the operator and the jaw 36 depresses the end of the lever 37 fulcrumed on the nose 38 and elevates at its other end the valve stem 39 which may be normally held down by a spiral spring or other means. 80

When the steam is admitted to the iron 85 by means of the tube 16 it will heat the same and may be confined therein, but on opening the cock 19 the steam and condensed water may pass outward and the steam allowed to circulate through the iron 90 to cause sufficient heat for practical purposes.

After the iron has been heated and its work begun the cock 22 may be opened by means of the knob 27 and the steam allowed 95 to moisten the goods. The amount of moisture may be very limited as the pressure and heat will cause it to spread over a wide area.

The handle of the ordinary iron is apt to 100 become uncomfortably hot to the serious inconvenience of the operator, so to protect his hand and to practically disconnect the handle from the iron, washers 40 of non-conductive material are interposed between 105 flanges 41 at the lower ends of the handle and the cover 41 of the iron and through which bolts 42 pass and also secure a diaphragm 43 of non-conductive material for heat while the knob 27 may also be of some 110 non-conductive or heat radiating material.

It is obvious that the parts may be other-

wise arranged or modified without departing from the essential features above described or from the scope of the appended claim.

5 What I claim as new is:

In a sad iron, the combination of an iron having an interior chamber and an L-shaped passage in its lower and front walls and outlets from the passage through the lower 10 wall, means for circulating steam through the chamber, an exterior pipe adapted to pass the steam from the chamber to the passage, a cock in the pipe, a handle secured to the iron, a diaphragm between the han-

dle and the iron, a bell-crank lever pivoted 15 to the handle and having a knob on one end and adjacent the front end of said handle, and a fork on the other end of the bell crank lever and adapted to open the cock.

In testimony whereof, I have signed my 20 name to this specification in the presence of two subscribing witnesses, this 3d day of June, 1919.

NATHAN RUBENSTEIN.

Witnesses:

A. W. BAKER,
JAMES F. DUHAMEL.
